UNITED STATES PATENT OFFICE.

RICHARD MARX, OF PHILADELPHIA, PENNSYLVANIA, ASSIGNOR, BY MESNE ASSIGNMENTS, TO THE TEMPERITE COMPANY, OF PHILADELPHIA, PENNSYLVANIA. A CORPORATION OF PENNSYLVANIA.

BLADE-HOLDER.

1,092,067.

Specification of Letters Patent. Patented Mar. 31, 1914.

Application filed December 18, 1912. Serial No. 737,487.

To all whom it may concern:

Be it known that I, RICHARD MARX, a citizen of the United States, residing in Philadelphia, Pennsylvania, have invented 5 certain Improvements in Blade-Holders, of which the following is a specification.

One object of my invention is to provide a novel form of relatively inexpensive box or package for razor blades whose construction shall be such as to permit of the convenient insertion and removal of said blades without danger of injury to the user.

Another object of my invention is to provide a case for holding razor blades with 15 novel means for ejecting or feeding out blades from the same, the arrangement of parts being such that after each blade may be partially ejected by the proper operation of the box lid, it may be conveniently 20 grasped by the fingers and removed.

I further desire to provide a blade container with a novel construction of sliding cover whereby the blades in the box may be successively engaged and ejected; the invention 25 also contemplating the provision of a novel form of spring for pressing the blades toward the cover.

It is also desired that the box or holder shall be so constructed as to hold the blades 30 in such manner that their cutting edges cannot come into contact with any part of said box, while owing to the peculiar shape of the latter the blades can be put into it in but a single position.

Another object of the invention is to provide a box or holder with means whereby 35 the blades therein may be forcibly separated and independently removed even though they should be held together by grease or some rust prevention compound.

These objects and other advantageous ends I secure as hereinafter set forth, reference being had to the accompanying drawings, in which,

Figure 1, is a perspective view of a blade-holding box constructed according to my invention; Fig. 2 is a perspective view of the lid or cover of the box; Fig. 3 is a perspective view of the preferred form of spring 45 for pressing the blades toward the cover; Fig. 4 is a perspective view of one form of razor blade for which the box illustrated is particularly designed; Figs. 5, 6 and 7, are perspective views illustrating respectively 50 the box with the cover in its closed position and also in two other positions assumed under conditions of use; Fig. 8, is a plan of the box with the cover in its closed position; Figs. 9, 10 and 11, are transverse vertical sections on an enlarged scale illustrating 55 the construction and use of my invention; and Figs. 12 and 13, are longitudinal vertical sections further illustrating the invention.

In the above drawings I have illustrated a 60 container or box particularly designed to receive safety-razor blades of rhomboidal outline as shown in Fig. 4 at X, each of said blades having at the extremities at its back edge two projections or lugs x, and at the 65 middle of said back edge an elongated projection x'. I therefore construct the blade container 1 so that, as shown in Fig. 8, it is substantially rhomboidal in plan and has laterally extending portions 2 at opposite 70 ends of one side in order to accommodate and closely fit the projections x of the blade. Obviously the box may be made of any 75 depth desired, depending upon the number of blades which it is required to hold and these latter are at all times pressed toward 80 the top or cover of the box hereafter described, by a special form of spring 3 of the construction shown in Fig. 3. Said 85 spring preferably consists of a flat plate or body 4 fitting into and having substantially the same outline as, the interior of the box and provided with two upwardly projecting tongues 5 preferably cut from or formed integral with said body 4.

It is understood that the tongues are of 90 resilient material and being cut from the body may be pressed down until they reenter the recesses from which they were originally cut so as to lie flush with the body, or 95 they may, when released, project so far upward as to extend immediately adjacent to or even engage the inner side of the cover. Obviously it is immaterial whether the body lies on the bottom of the box with the 100 tongues projecting upwardly or whether said tongues engage the box bottom and act to force the body toward the cover. Said cover is illustrated at 6 in Fig. 2 and consists of a rhomboidal plate having substantially the width of the box 1 though of a slightly greater length than the same. For 105 slidably retaining this cover on the box, the

latter is provided with two guideways 7 along its opposite transverse top edges, and these are nicked or pressed inwardly as indicated at 8 in Fig. 8 to provide internal 5 stops designed to enter elongated slots 9 in the opposite transverse edges of the cover 6; the arrangement and proportioning being such that the said cover may be moved from a position immediately over the top of the 10 box to a position in which about one-third of its width projects beyond one longitudinal edge of the box, as shown in Fig. 6. Said cover is preferably provided with stiffening ribs 10 which also serve as finger holds 15 and at the ends of its front edge has two downwardly formed projections or lugs 11 so placed as to be capable of falling back of the lugs α of the razor blades.

Under conditions of use a number of 20 safety razor blades is placed in the box upon the upwardly projecting tongues 5 of the spring body 4 and after they have been pressed into the box against the action of said tongues, until the uppermost one is 25 flush, with the top edges of said box, the cover 6 is applied by entering first one end and then the other in the respective guideways 7. Obviously the blades X are forced toward the cover by the spring tongues 5 so 30 that they occupy the positions illustrated in Figs. 9 and 12 for example, and when it is desired to remove one of them, the box is preferably allowed to rest upon the first and second fingers of the hand while the lid or 35 cover 4 is moved by the thumb of the user, back into the position shown in Fig. 6. It will be noted that the guideways 7 are so proportioned that when the box is closed as shown in Fig. 5, the body of the cover is 40 spaced away from the plane of the top edges of the box by a distance substantially equal to the thickness of a single razor blade. Consequently when the cover is moved back into the position shown in Fig. 6, the spring 45 tongues 5 so act on the uppermost razor blade that its body is held in contact with the under side of said cover, while the projections 11 of the latter drop behind the lugs α of said blade, whose front or blunt edge 50 now lies wholly above the plane of the top edges of the box. If now the cover 6 be moved forwardly until it lies immediately over the box, as shown in Fig. 7, the top razor blade is moved so that its blunt edge 55 projects beyond the side of the box for a sufficient distance to enable it to be conveniently grasped and removed.

By another rearward sliding of the cover 6 into the position shown in Fig. 6, the projections 11 drop behind the lugs α of another blade, which thereafter may be removed as previously described.

With the box constructed as noted, all danger of injury to the user from the edges 65 of the razor blades is effectually prevented,

since by the proper manipulation of the cover their blunt edges are presented to the user and their sharpened edges are completely protected until they have been removed from the box or container. At the 70 same time it is not possible for the cutting edges of the blades to be injured by contact with any part of the box since their lugs α are normally held in correspondingly formed extensions at one side of the box and 75 are only removed when said lugs are positively engaged by the projections 11 of the cover.

It is of course to be understood that the box or container, together with its cover and 80 spring plate, are by no means necessarily rhomboidal in outline, since they may be made rectangular or in other forms without essential modification of my invention, although one important advantage of the box 85 made as shown, lies in the fact that the blades can be placed in it in but one position and consequently all have the same side uppermost as required when the sides of the cutting edge are differently ground. 90 Moreover, while for the particular form of razor blade shown in Fig. 4 I provide the projections 11 of the cover so that they will engage the lugs α at the ends of one edge of said blade, it is to be understood that 95 without departing from my invention, the projections or engaging portion or portions of the slideable cover may be located at any suitable point thereon as may be necessary to permit them to properly engage a projection or projections formed anywhere on a razor blade or to enter any recess or recesses thereof, for the purpose of imparting to such blade a movement as will draw it from the interior of a box or package, into 100 a position to allow of its being conveniently grasped and removed.

I claim:—

1. The combination in a blade holder, of a container; a cover movably guided thereon and spaced away from the top edge thereof by a distance substantially equal to the thickness of a blade; means for pressing blades in the container toward said cover; and means on the cover for engaging portions of the ends of the topmost blade in the holder to remove the same when said cover is reciprocated.

2. The combination in a blade holder of a container having two of its opposite top 120 edges extended and bent to form guide ways having a U-shaped section, each guide way being pressed in to provide a stop; a cover slideable in the guide ways and having portions cut away to receive said stops while 125 permitting movement of said cover; and means for forcing blades in the container toward the cover.

3. The combination of a box having a body portion and an extension thereto; with 130

5 a cover movably guided on the box and having a projection placed to engage a portion of a razor blade extending into said box extension, when the cover is moved on the box.

10 4. The combination of a blade holder consisting of a box having a body portion and an extension thereto; with a series of blades each having a body and an extension, the extension of each blade entering the extension from the box body and being held thereby in a position in which the cutting edge of the blade is retained out of engagement with the wall of the box.

15 5. The combination of a blade holder consisting of a box having a body portion and a plurality of oppositely placed extensions thereto; with a series of blades each having a body and a plurality of extensions, the extensions of each blade entering the extensions from the body of the box, and the blade being held thereby in a position in which the cutting edge thereof is retained out of engagement with the wall of the box.

20 6. The combination in a blade holder of a box having lateral oppositely placed extensions; a cover slidably mounted on the box; means for limiting movement of the cover between the position in which it closes

25 the box and the position in which one of its edges is spaced away from the front edge of the box, to provide an opening; with projections on said edge of the cover extending downwardly in position to engage projections from the ends of a razor blade lying within said opposite extensions of the box.

30 7. The combination of a blade holder consisting of a box having a body portion and a plurality of oppositely placed extensions thereto; a series of blades each having a body and a plurality of extensions respectively lying within the extensions of the box body so as to hold the cutting edges of the blades out of engagement with the adjacent portion of the box; and a cover 35 movably mounted on the box having projections respectively placed to engage the extensions of the blades as said cover is moved, to successively feed said blades from the box.

40 In testimony whereof, I have signed my name to this specification, in the presence of two subscribing witnesses.
